UNITED STATES PATENT OFFICE.

HERMAN R. SMITH, OF DOUGLASTON, NEW YORK, ASSIGNOR TO RAYMOND CONCRETE
PILE COMPANY, OF NEW YORK, N. Y., A CORPORATION OF NEW JERSEY.

METHOD OF DRIVING COMPOSITE FILES.

Application filed March 30, 1926. Serial No. 98,441.

This invention covers an improved method and apparatus for driving composite piles.

A composite pile, as usually erected, comprises a wooden pile driven below the earth 5 surface or water level, upon which is superimposed a concrete column, the wooden pile and concrete column being so united as to form a unitary pile structure. For convenience of description the lower portion of 10 each composite pile is referred to as a wooden pile, but it may be of other material if desired.

In forming or erecting a composite pile the usual practice is to first form a tenon 15 on the head of a wooden pile, and then drive the pile until its head is at or near the ground level, then place upon the head of the wooden pile the core and shell of the concrete shaft, then drive the wooden pile, 20 core and shell to the required depth, then remove the core, and finally fill the shell with concrete to form the completed structure.

The driving of the piles is generally done 25 with a pile driver including a pair of vertical guides or "leads". Between the leads is mounted the driving hammer, controlled by suitable hoisting tackle. The whole driver structure usually rests on rollers supported 30 by timbers laid on the surface of the ground. After the driving of a pile is completed the entire machine is moved on the rollers into position to drive the next pile.

The driving of the wooden piles is a com- 35 paratively simple operation, it being only necessary to fit the pile with a driving cap to avoid damaging the upper end of the pile, and then drive the pile.

However, the driving of the upper portion 40 of the composite structure is a more difficult and involved operation. The heavy core must be constantly handled, together with the shells which are ultimately left in the ground to form the concrete portion of the 45 pile. After the core and shell have reached the desired depth the core is raised from the shell by cables attached to the hammer and is held suspended in the air between the leads while the shell for the next pile is 50 fitted to it.

If it were desired to drive a wooden pile 55 between the driving of two concrete shafts or columns it would be necessary to first lay down the core so as to free the hammer for the driving operation on the wooden pile,

and then pick up the core again for the driving of the concrete shaft.

Composite piles of ordinary length are driven in one operation, that is, the core is mounted on the wood pile and they are 60 driven together. When the length exceeds a certain figure, however, it is not practical, on account of head room required, to drive the complete pile in one operation. For such situations the apparatus and 65 method of the present invention have been worked out.

On account of the difficulty of handling the core, it has been impractical, with 70 methods and machinery now in use, to complete each composite structure in one series of operations. Instead, it has been customary to first drive a number of wooden piles in the area conveniently reached during one "run" of the driver, then pick up the 75 core and go back over the same run a second time, driving the wooden piles further with cores and shells superimposed.

The objections to the above method are 80 many. In some grounds the wood pile "sets" very quickly and is very difficult to drive if not followed down promptly. Under such conditions only a few wooden piles can be driven before going back and 85 finishing the driving with the core.

Another objection is that the concrete 90 gang is idle while the wooden piles are being driven. Another objection is the time and labor required in going over the same ground twice. This is aggravated when the 95 piles are scattered and very few can be reached from one length of run, for under such conditions it becomes necessary to frequently pick up and lay down the core or tear down and rebuild the runs.

Another objection to the ordinary method 100 is found in rainy weather, for if some wood piles are driven and then work has to be suspended until the next day on account of rain, the wood piles already driven will be set so hard as to offer undue resistance in following them down with their cores.

In composite pile work it is usually de- 105 sirable to get the top of the wood pile just below permanent water level, making the concrete tops the same length. When the piles are driven to a hard strata which is sloping, wood piles of different lengths are required. The exact slope or conformation of the hard strata is generally unknown, 110

therefore when the piles are some distance apart it becomes necessary to drive only one or two piles before following down in order to learn what length of wood pile is required. The length of the concrete portion of the pile is limited by the length of the core, and if too many wood piles are driven before following down it may be found that some wood piles are too short to reach bottom with the available length of core.

All the above disadvantages are overcome by my improved apparatus and method, which in its preferred form, comprises a driver equipped with two hammers suitably guided and arranged so that one hammer is always available for driving wood piles, without first laying down the core, and one hammer is always available for placing and driving the core, without first having to pick up the core.

The use of my apparatus permits the driving of a wood pile followed immediately by the placing and driving of the core, thereby avoiding much handling and rehandling of the core and overcoming all the other objections enumerated above. Each pile is finished at once, so there is no opportunity for the ground to set up; it is not necessary to go back over the ground again to follow the piles down; the concrete gang is kept busy continuously; the probable length of the pile next to be driven can be fairly accurately gauged from the length of the one just completed; and there are no piles remaining unfinished in the event of rain.

In the drawings,

Fig. 1 is a front view of the apparatus while driving a wooden pile, the core being suspended from its hammer.

Fig. 2 is a side view of the apparatus in Fig. 1, showing the boiler, engine, and portions of the hoisting and slewing apparatus.

Fig. 3 is the same view as Fig. 2 after the wooden pile has been driven and its hammer raised.

Fig. 4 is a front view of Fig. 3 after the driver has been swung to bring the core and its hammer directly above the driven wood pile, and after the core and shell have been placed on top of the wood pile preparatory to following it down.

Fig. 5 is a diagrammatic plan view showing the driver in two positions on its turntable.

Referring to Figs. 1 and 2, 10 is the turntable of the pile driver structure, upon which is erected the tower 12 comprising the usual trussed members and vertical guides or leads 14. Between the leads 14, and guided by them for vertical movement, is the hammer 16, supported by cable 18 passing over head sheave 20 to a drum actuated by hoisting engine 22.

Fast to the side of tower 12 is the vertical

lead 24 designed to guide the second hammer 26 which is supported by cable 28 passing over head sheave 30 to another drum actuated by engine 22.

Turntable 10 rests on bed sill or base 32 upon which the entire pile driver may be rotated by cables 34 actuated by engine 22. Underneath the base are skids 36 resting on rollers 38, which in turn rest on runways 40 resting on ties 42 on the ground. 44 is the boiler supplying steam to engine and hammers. 46 designates a wooden pile being driven by hammer 26. 48 designates the core on which is mounted a shell 50, both being supported from the bottom of hammer 16 in position to be placed on top of pile 46 when it has reached its proper depth (see Figs. 3 and 4) after which it will be followed down by core 48 and shell 50 driven by hammer 16. In order to align core 48 and shell 50 with pile 46, the pile driver structure is rotated slightly by turntable 10, as indicated in Fig. 5.

The wooden pile 46 is usually provided with a tenon 52 on its upper end to aid in making a proper joint with the concrete superstructure.

After the core and shell have been driven to the proper depth, the core is withdrawn and held suspended from hammer 16 as in Fig. 1 while the next wooden pile 46 is driven by hammer 26. During the driving of this wooden pile the shell 50, just driven, is filled with concrete.

Thus it will be seen that the use of my improved apparatus comprising two hammers, either of which may be instantly aligned with the pile, enables the various operations of erecting composite piles to be carried out in very advantageous sequence, and permits the finishing of each composite pile structure in a practically continuous operation.

It is to be understood that the invention is not limited to the constructions herein specifically illustrated but may be embodied in other forms without departure from its spirit.

I claim:

1. In an apparatus for forming and driving a composite pile, in combination, a plurality of hammers and means to align any of said hammers with the pile. 115

2. In an apparatus for forming and driving a composite pile, in combination, a core, a plurality of hammers, means to align any of said hammers with the pile, and means to support said core out of alignment with the pile. 120

3. In an apparatus for forming and driving a composite pile, in combination, a core, a plurality of hammers, means to align any of said hammers with the pile, means to support said core out of alignment with the pile, and means to move said core into alignment therewith. 130

4. In an apparatus for forming and driving a composite pile, in combination, a core, a plurality of hammers, means to align any of said hammers for operation on the pile, 5 means comprising one of said hammers for supporting said core out of alignment with the pile, and means to move said core into alignment with the pile.
5. In an apparatus for forming a composite pile including a wooden pile sur- 10 mounted by a concrete column, in combination, a structure, means carried by said structure for driving the wooden pile, a core, a shell mounted on said core, means 15 carried by said structure for supporting said core and shell out of alignment with the wooden pile while it is being driven, and means for subsequently mounting said core and shell on the wooden pile.
- 20 6. The invention set forth in claim 5 in which means is provided for driving said core, shell and wooden pile after said core and shell are mounted on the wooden pile.
7. In an apparatus for forming a composite pile comprising a wooden pile sur- 25 mounted by a concrete column, in combination, a hammer for driving the wooden pile, a core, a shell mounted on said core, means for mounting said core and shell on the 30 wooden pile, and a hammer for driving said core, shell and wooden pile after mounting, said last mentioned hammer serving to support said core and shell out of alignment with the wooden pile while the wooden pile is 35 being driven.
8. A method of forming and driving a composite pile including a wooden pile sur- 40 mounted by a concrete column, which comprises the provision of a movable support, a driving means, a core and a shell, driving the wooden pile while the core and shell are held by said movable support out of alignment with the wooden pile, moving said support to mount said core and shell on the 45 wooden pile, driving the core, shell and wooden pile, removing the core by said movable support, and filling the shell with concrete.
9. A method of forming and driving a composite pile including a wooden pile sur- 50 mounted by a concrete column, which comprises the provision of a core and a support therefor, driving a wooden pile while supporting the core out of alignment therewith, moving the support to align the core with 55 the driven pile, driving the core and pile, and replacing the core with concrete.
10. A method of forming and driving a composite pile including a wooden pile surmounted by a concrete column, which 60 comprises the provision of a core and a shell, driving a pile while vertically sup- 65 porting the core and shell out of alignment therewith, mounting the core and shell on the driven pile, driving the pile further with the core and shell mounted thereon, removing the core, and filling the shell with concrete, substantially as described.
11. A method of forming and driving a composite pile including a wooden pile sur- 70 mounted by a concrete column, which com- 75 prises the provision of a core, a shell, and two hammers, driving a wooden pile with one hammer while supporting the core and shell from the second hammer, mounting the core and shell on the wooden pile, driv- 80 ing the core, shell and wooden pile with the second hammer, withdrawing the core from the shell and filling the shell with concrete.
12. A method of forming and driving a composite pile including a wooden pile sur- 85 mounted by a concrete column, which com- 90 prises the provision of a core, a shell, and two hammers, driving a wooden pile with one hammer while supporting the core and shell from the second hammer, moving the second hammer to mount the core and shell on the wooden pile, driving the core shell and wooden pile further with the second hammer, withdrawing the core from the shell by means of the second hammer, and filling the shell with concrete.

In testimony whereof I hereto affix my signature.

HERMAN R. SMITH.
